TRANSFERABLE LOAD CONTAINERS
John Semple Penman, 9 Queensberry Motor Works,
Dumfries, Scotland
Filed June 23, 1959, Ser. No. 822,369
Claims priority, application Great Britain June 24, 1958
5 Claims. (Cl. 214—38)

This invention relates to a transferable load container of the type having at least two pairs of longitudinally spaced followers adapted to project from both sides of the container at the front and at the rear of the container in such wise as to engage at least one pair of equi-spaced ramps in a loading bay, the ramps each presenting a linear inclined portion and a horizontal portion. There may be a linear inclined portion at both ends of each ramp.

The primary object of the present invention is to provide for ease of transferring the container from a platformed motor vehicle to a flat rail truck and vice versa.

In the specification and in the claims, all references to "front" and "rear" as applied to the container relate to the container as viewed in the normal direction of travel of the container when mounted on a vehicle or on a rail truck.

A transferable load container, of the type referred to, according to the invention is provided at the front and at the rear with a flap pivoted about a horizontal axis to the underside of the container, and a lever operatively connected to each flap and operable to cause the associated flap to swing about its pivot from a position in which the flap is substantially horizontal to a position in which the flap is inclined downwardly from the base of the container and vice versa.

Two forms of transferable load container, of the type referred to, according to the invention are illustrated in the accompanying drawings in which:

FIG. 1 is a side elevation of the first form of container which is of the type used for transporting goods by a rail truck.

FIG. 2 is an end view of the first form.

FIG. 3 is a side elevation of ramps for receiving the container.

FIG. 4 is a section on the line 4—4 of FIG. 3.

FIG. 5 is a side elevation, drawn to a larger scale, than the preceding figures, of one of the flaps and its associated operating mechanism.

FIG. 6 is a fragmentary section on the line 6—6 of FIG. 5.

FIG. 7 is a fragmentary section on the line 7—7 of FIG. 6.

FIG. 8 is a fragmentary section on the line 8—8 of FIG. 1.

FIG. 9 is a side elevation of the second form of container which is of the type used for transporting goods by a motor vehicle.

FIG. 10 is an end view of the second form of container.

FIG. 11 is a side elevational view showing a flat bottomed motor vehicle in the loading bay between the ramps and a transferable load container located on the ramps above the motor vehicle, the load container being in the position either in which it has been moved onto the ramps from the motor vehicle or in which it is ready to be moved off the ramps onto the motor vehicle, by backing the motor vehicle.

FIG. 12 is an end view partly in section taken from the left in FIG. 11, with certain parts of the container omitted.

Referring to the drawings in which like numerals denote like parts, 11 denotes the body of the container. 12 denotes each of two pairs of longitudinally spaced fol-

2

lowers having rollers 20 (FIG. 8) and adapted to project from and to be retracted into both sides of the container 11 at the front and at the rear of the container 11 in such wise as to engage a pair of equi-spaced or parallel ramps 13, 14 (FIGS. 3 and 4) in a loading bay, the ramps 13, 14 each having a horizontal portion 15 and, at both ends, a linear inclined portion 16.

The container 11 is provided at the front and at the rear with a flap 17 pivotally mounted on a tube 18 journalled for turning movement about a horizontal axis in the underside of the container 11. One end of each tube 18 is operatively connected to a cranked lever 19 located exteriorly of the container 11 and movable to cause the associated flap 17 to swing about its pivot 18 from a position in which the base of the flap 17 is substantially horizontal to a position in which the flap is inclined downwardly from the base of the container 11 and vice versa.

Each lever 19 is movable through a preselected arc in a guide 21 (FIG. 5) secured to the associated side of the container 11. The lever 19 is arranged, when the associated flap 17 is in the raised position, to be engaged by a catch 22 on the associated side of the container 11 and, when depressed and moved sideways slightly clear of the catch 22, to spring clear of the catch 22. The flaps 17, when the associated levers 19 are disengaged from the catches 22, are normally free to swing downwardly under their own weight.

Each flap 17 extends for slightly less than the width of the container 11.

When the flaps 17 are inclined downwardly from the container 11, the front flap 17 is inclined towards the front of the container 11 and the rear flap 17 is inclined towards the rear of the container 11.

In practice, when it is desired to transfer the container 11 from a motor vehicle, such as the flat bottomed motor vehicle 23 shown in FIGS. 11 and 12, to a flat rail truck, the followers 12 are projected from the container 11 and the flaps 17 are located with their bases in horizontal positions adjacent to the underside of the container. The vehicle is reversed or backed along a rail track, which may be provided with guides for the vehicle wheels, to one end of the loading bay where the rollers 20 on the rear followers 12 engage the adjacent inclined portions 16 of the ramps 13 and 14. The lever 19 toward the front of the vehicle is actuated to release it from the catch 22 and permit the associated flap 17 to tilt downwardly and rest on the platform of the motor vehicle.

Now, with the motor vehicle in position to be moved between the ramps and the rollers 20 at the rear respectively engaging the adjacent portions 16 of the ramps, continued reverse movement of the vehicle between the ramps causes the container 11 and the flap 17 at the front to slide along the vehicle platform until the flap 17 engages the front of the body of the vehicle above the platform or a rail 24 provided for that purpose. This engagement stops the sliding of the container on the vehicle platform and the rollers 20 at the rear roll respectively up adjacent the inclined portions 16 of the ramps 13 and 14. This movement is then continued until both pairs of rollers 20 are rolled onto and along on the ramps until they rest on the horizontal portions 15. This operation raises the container 11 clear of the vehicle platform so that its entire weight is supported by the ramps 13 and 14. The released lever 19 toward the front of the vehicle is then actuated to raise the associated flap 17 and the lever is placed under the latch 22.

The motor vehicle is now driven away from between the ramps 13 and 14 and a flat rail truck is then moved to a position between the ramps under the container 11. The appropriate lever 19 is then actuated to lower the associated flap 17 onto the flat rail truck so that it is in position to engage a stop or rail on the truck for the

purpose of rolling the container in the direction of movement of the truck, when the truck is shunted out from between the rails 13 and 14. As the rollers 20 move along the ramps, they in turn roll down the inclined portions 16 at the end, in the direction of movement of the rail truck until the container 11 is clear of the ramps 13 and 14 and is supported by the rail truck. The released lever 19 is then actuated to raise the associated flap 17.

It will be understood that the inclined portions 16 at the respective ends of the ramps 13 and 14 are provided so that a vehicle or rail truck may enter or leave from either end and so that a container may be rolled on or off from either end of the ramps. It will furthermore be understood that flaps 17 are provided at both ends of the container so that it may be actuated from either end to move it onto or off the ramps.

The above described process is repeated when it is desired to transfer the container from a rail truck to a platformed vehicle, such as the motor vehicle 23.

It is to be understood that any desired number of containers may be transferred from vehicles to the loading bay and removed by a corresponding number of trucks, or a plurality of containers transferred from rail trucks to the loading bay may be removed singly by motor vehicles.

What is claimed is:

1. A transferable elongated load container having longitudinally spaced followers at both sides of said container, means for projecting said followers from said sides to a position for engaging a pair of parallel spaced ramps, a member mounted transversely of the underside of the container at each end portion thereof for turning movement about a horizontal axis, a flap mounted on each of said members and extending therefrom; and a lever connected to each of said members and operable to turn said member on said axis and swing the associated flap from a position in which the flap is substantially horizontal to a position in which the flap is inclined downwardly from the underside of said container and from a position in which said flap is inclined downwardly from said underside to a position in which said flap is substantially horizontal.

2. A transferable container as claimed in claim 1, in which the member mounted transversely of the underside of the container at each end portion thereof comprises a tube journaled for turning movement about a horizontal axis, one end of said tube projecting from a side of said container, and said lever being connected to the projecting end of said tube for effecting the turning movement of the tube and the swinging of the flap.

3. A transferable container as claimed in claim 1, in which each of said levers is cranked, and a catch on the side of the container located in a position for engagement by the lever when the associated flap is in its substantially horizontal position.

4. A transferable container as claimed in claim 1, in which each flap extends substantially the width of the container.

5. In a transferable elongated load container of the type to be transferred from the platform of a vehicle to a pair of spaced ramps between which the vehicle moves during the transfer and in which the container is provided with rollers at each side at each end for engaging the ramps, the improvement comprising a member mounted transversely of the underside of the container at each end portion thereof for turning movement about a horizontal axis, a flap mounted on each of said members extending therefrom in the direction of the end of the container at which the flap is located, each flap also extending substantially the width of the container, and a lever connected to each of said members at the side of the container and operable to turn said member on said axis and swing the associated flap from and to a position in which the flap is substantially horizontal to and from a position in which the flap is inclined downwardly from the underside of the container.
